UNITED STATES PATENT OFFICE.

EDWARD J. KING, OF ROCHESTER, NEW YORK, ASSIGNOR TO THE CO-OPERATIVE FOUNDRY COMPANY, OF SAME PLACE.

DESIGN FOR A COOKING-STOVE.

SPECIFICATION forming part of Design No. 18,302, dated May 8, 1888.

Application filed March 29, 1888. Serial No. 268,877. Term of patent 7 years.

To all whom it may concern:

Be it known that I, EDWARD J. KING, of Rochester, in the county of Monroe and State of New York, have invented a new Design for a Stove, which is fully set forth in the following specification and shown in the accompanying photograph.

This newly-designed stove is intended for cooking purposes; and it consists, essentially, of a base-section or stand, A, body B, column C, and upper section or high closet, D.

The stand is rectangular in plan, formed with a base-strip, c, extending around four sides thereof, having rounded corners a and a foot, b, at each corner. The lower edge of the base-strip on each side of the stove is formed in three curves, d g g, spanning the space between either two adjacent feet, the small curve d at the middle being convexed downward and the larger ones, g g, on either side being convexed upward. A plain marginal band or border, e, of uniform width, follows the contour of the curves, reaching from foot to foot on each side of the stand. At its upper edge the stand is formed with a molding, f, and on the field between the molding and the band e the base-strip is carved into raised scroll-work a' and other ornamentation, as shown. The feet are each formed with a rosette, i, at the swell portion thereof, encircled by scrolls and leaf. The rounded corners a of the base-strip are ornamented with shields.

The body B of the stove is formed with a plain slanting band, d', at its upper edge, and a similar band, h, at its lower edge, which latter band meets the molding f of the stand, said band h extending around the bottom of the reservoir E also. The oven-door k is formed with plain rounded diedral angles l and a convex marginal fillet, n, covered with a running ornamentation consisting of parallel inclined lines covering alternated triangular areas within an edge strip, o. This door is further ornamented with raised scroll-work p, with involutes, and a plate, r, containing within an eccentric circular bead a tile, b', showing the bust of a knight, which tile, however, is not new. Beneath the door is a horizontal shelf, c', with plain uncut edge, the shelf being formed with open scroll-work.

The fire-door s is formed with a central tile or rosette, t, of common kind, surrounded by

concentric rings, the outer being heaviest, and cut into overlapping scales or shells. The door is further formed with plain rounded angles and fillet u, like the fillet n of the oven-door. Beneath the door s is a swelled panel, v, ornamented with oppositely-turned involutes w and other figures, as shown.

The side of the reservoir E is ornamented with a common tile rosette, d', at the middle of a raised panel, c', the rosette being encircled by concentric rings, like those of the door s, and other raised ornamentations, the raised panel being surrounded on three sides by a 6c fillet, c', similar to the fillet n of the oven-door. The under surface of the reservoir is curved upward, as shown at e'.

The front door, f', has its rounded diedral angles g' cut into running ornamentations, like that of the fillet n, and formed with four circular mica openings, h', together forming an arch. The feed-door k' is not held to be new in design.

The column C, up through which the smoke passes, has an oval front face or side, which is ornamented at the middle with a circular tile surrounded by raised scroll-work i', as shown. Lateral extension pieces n', ornamented with open scroll-work, are placed at 8c each side of the column C, from which project horizontal circular shelves o' to the right and left.

The upper section or high closet, D, is prismatic in form and mounted by an ornamental back guard, r', formed of open scroll-work. At the upper and lower edges this section is formed with plain inclined bands p', with projecting end panels, u', and swelled doors t'. These doors and panels are rectangular in plan, 9c having rounded diedral angles v' and curved fillets ornamented by markings, the same as the corresponding parts of the doors of the body of the stove. The doors are ornamented with vertical bands s', having a square field in each placed with angles in horizontal and vertical lines. The surfaces of the doors at each side of these bands are ornamented with raised scroll-work a', as shown, and vertical strips b' of leaf and scroll work, within which are placed the knobs of the doors.

The raised or swelled end panels, u', are ornamented with leaf and scroll h'.

What I claim as my invention is—

1. In a design for a cooking-stove herein shown and described, the stand or base-section A, consisting of the base-strip c, having its lower edge formed into reverse curves d g g, 5 traversed by marginal bands e, and a molding, f, around its upper edge, the field between said molding and bands being ornamented with scroll-work, as shown, and shields at the rounded corners, substantially as shown and 10 described.
2. In a design for a cooking-stove herein shown and described, the door k, consisting of a swelled or outwardly-projecting body formed with rounded or convex dihedral angles l and 15 peripheral strip o, with convex fillet n, worked with running ornamentations, raised scroll-work, and an ornamented plate, r, holding a tile or figure in an eccentric circle, substantially as shown.
3. In a design for a cooking-stove herein shown and described, a door, s, formed with a swelled body, with rounded convex dihedral angles having a central tile or figure inclosed by concentric circles, the outer one being the 25 largest in cross-section and carved into overlapping scale or shell work, and a fillet, u, formed at three sides of the door, marked with running ornamentations, substantially as shown.
4. In a design for a cooking-stove herein shown and described, a door, f', formed with an outwardly-swelled body having its dihedral angles made convex and marked with running ornamentations, as shown, circular openings 30 being formed through the front plate of the door in such manner that a line passed through their centers would be arched or concaved downward, substantially as described.
5. In a design for a cooking-stove herein shown and described, the body-section B, 40 formed with uncut inclined edges or bands d' and h at its respective upper and lower parts, a reservoir formed with a curved under surface, and projecting side panels, c', with fillets e' on three sides thereof, said panels being further formed with scroll-work and circles surrounding a central tile, a swelled panel v, 45 ornamented with involutes w and other figures, as shown, a shelf, c', cut through with open scroll-work, and ornamented side and 50 front doors, k, g, and f', substantially as shown.
6. In a design for a cooking-stove herein shown and described, a column, C, extending upward from the body-section B of the stove, formed with an oval or curved front, ornamented as shown and provided with right and left side extensions, n', consisting of open scroll-work and lateral oppositely-projecting shelves o', substantially as shown. 55
7. In a design for a cooking-stove herein shown and described, an upper prismatic section, D, formed with upper and lower uncut bands, p', rectangular projecting end panels, u', formed at their four sides with fillets w', marked with running ornamentations, swelled 60 front door, l' t', mounted with vertical cross-bands s' s', and formed with raised scroll-work on each side of said cross-bands and fillets w' on three sides of each of said doors, and a vertical back guard, r', of open scroll-work at the 65 rear of said prismatic section, substantially as described. 70

EDWARD J. KING.
